James J. Aquilina(57) **CLAIM**

The ornamental design for a lighting device, as shown and described.

DESCRIPTION

FIG. 1 is a front perspective view of a lighting device showing my new design;

FIG. 2 is a front elevation view thereof;

FIG. 3 is a left side elevation view thereof;

FIG. 4 is a right side elevation view thereof;

FIG. 5 is a top plan view thereof; and,

FIG. 6 is a bottom plan view thereof.

The dashed broken lines in the Figures show unclaimed portions of the lighting device. The long dash-short dash-long dash broken lines in the Figures show unclaimed boundaries between claimed and unclaimed subject matter.
